(57) **CLAIM**

The ornamental design for an eye glasses retainer, as shown and described.

DESCRIPTION

FIG. 1 is a perspective view of an eye glasses retainer showing my new design;

FIG. 2 is a rear view thereof;

FIG. 3 is a front view thereof;

FIG. 4 is a side view thereof;

FIG. 5 is another side view thereof;

FIG. 6 is a bottom view thereof; and,

FIG. 7 is a top view thereof.

The broken lines shown in the drawings are included for the purpose of illustrating unclaimed portions of the eye glasses retainer and form no part of the claimed design.
